ASH RECEPTACLE

Richard R. Kienle, New York, N. Y.

Application February 9, 1937, Serial No. 124,813

6 Claims. (Cl. 131—51)

The object of the present invention is to provide an improved ash tray having a rotatable cover integral with a perforated tray through which the ashes are permitted to drop out of sight and into the receptacle.

Another object of the invention is to provide an ash tray in which unsmoked and discarded ends of cigars or cigarettes may in the same operation covering the receptacle be deposited within the receptacle.

Still a further object of the invention is to provide an ash tray in which fresh air is kept from discarded but still lit cigar or cigarette ends within the receptacle thus extinguishing them and preventing objectionable smoke from the receptacle.

Still further and other objects are obvious from the description of my preferred constructions and the annexed drawing in which:

20. Figure 1 shows a top view with the cover closed;

Figure 2 a section along line 2—2 of Figure 1 showing the front elevation of my ash receptacle;

Figure 3 an end section along line 3—3 of Figure 1 with the cover closed;

25. Figure 4 an end section similar to that of Figure 3 showing the cover open and the tray in place; while

Figure 5 discloses an alternative form of construction, and

30. Figure 6 shows a partial top view in the direction of the arrow of Figure 5.

The frame 1 of my ash receptacle fits onto the body 2, of any convenient shape but shown as a rectangular box, by a slide fit, or other convenient means, over shoulder 3. The frame may be provided with a number of depressions 4 providing cigar, cigarette, or pipe stem rests. A solid cover 6 is rotatably mounted within said frame 1 and covers snugly the whole of the interior field of the frame. Tongue 7 extends from the cover and recesses 5 are provided at either side of the frame. The lower part of the tongue 7 rests against the inner portion of the recess which constitutes a stop for the tongue, while 45 there is sufficient clearance between the outer portion of the recesses and the outer portion of tongue 7 to permit the fingering thereof.

Depending projections 8 are provided centrally of each side member of frame 1 to rotatably 50 support the cover assembly by means of pins 10. The rotatable cover assembly comprises the solid cover 6, the side members 9 which are approximately triangular shaped but may be of any other convenient form, and the perforated tray 55 12. Perforated tray 12 is of the same exterior

dimensions as cover 6 and thus is likewise adapted snugly to fit within the whole of interior field of frame 1. For convenience of manufacture tongue 7 is made integral with tray 12, but it could as readily be integral with cover 6. Tray 5 12 is connected along one of its longitudinal edges to a longitudinal edge of cover 6, while its sides are connected to the hypotenuses of side members 9. Tray 12 is cylindrically shaped parallel to the axis of rotation of the cover assembly as shown at 13 so that when within the field of the frame it is depressed most along its central longitudinal axis.

Inverted U-members 14 are affixed to and supported by projections 8 and have a hook 15 at 15 their upper portion. Hook 15 is so positioned as to be approximately over the pin 10 on which the rotatable cover assembly is supported. A coil spring 16 has one end affixed to said hook while the other end is connected about midway 17 of 20 the free side 18 of side member 9. At the interior edge of the frame side which the perforated tray faces when cover 6 is within the field of the frame, a solid depending projection 19 with solid side walls 20 is provided for the purpose 25 hereinafter set forth. The remote leg 22 of the inverted U-member 14 is springy and conveniently made in such form as to provide a friction latching action with a depression 23 in the side walls of body 2 when the frame is in place. 30 The latching means is such that by the application of a relatively slight pull on the frame assembly the latter may be readily removed as a unit from the receptacle permitting cleaning.

When the ash receptacle is not in use the solid 35 cover is within the interior field of the frame and does not present the unsightly appearance of smoke remnants such as ashes or partially consumed cigarettes or cigars. By grasping tongue 7 the cover may be rotated thereby tensing coil 40 springs 16. After midpoint 17 has reached its lowermost position the springs on continued rotation of the rotatable assembly will tend to snap the perforated tray into its use position within the interior field of the frame and will retain 45 it there until tongue 7 is pushed deliberately in the opposite direction. Thus whether cover 6 or tray 12 is within the field of the frame, spring tension positively retains them in such position. When the perforated tray is within the 50 field, ashes readily drop through the perforations and out of sight but are prevented from falling into the main body 21 of the receptacle by the solid cover 6 and the solid projection 19 with its solid end members 20. The solid projection 19 55

is so formed that, as best shown in Figure 4, the cover and the projection retain the ashes for the time being. This also serves the additional function of limiting the combustible content of the atmosphere within the main body 21 of the receptacle thereby putting out any still burning tobacco therein. Thus practically no smoke escapes from the main body through the perforated tray while the latter is in the field. Perforations 25 are preferably of such dimensions that only ashes can fall through, and to deposit unsmoked and unsmokable ends of cigarettes or cigars within the main body they must be laid on the tray and the tray rotated by tongue 7, such rotation dumping them into the main body of the receptacle, for in such position, as best shown in Figure 3, there is sufficient clearance between the rotatable elements and the projection 19. In the same operation, and in the same manner, ashes within the rotatable elements are deposited within the main body. My ash receptacle thus always has a presentable appearance, and its interior needs cleaning only at relatively long intervals. Body 2 can obviously be conveniently provided with compartments at its sides and bottom for cigarettes, cigars, and matches.

An alternative rotatable cover assembly is shown in Figures 5 and 6 in which ashes within the rotatable element may be deposited into the main body of the receptacle without rotating the perforated tray from within the field of the frame. In this case, a recess 26 is provided in the perforated tray 12 and the solid cover 6 instead of being integral with the tray is hinged as shown at 27 along one of the tray's edges at either side of the recess, that is, to both sides of the recess. Recess 26 permits a limited independent movement of tongue 7 which in this construction is made integral with the hinged solid cover. The lower end of the cover 28 and the sides of the cover are retained against the longest side of triangular member 9 by coil spring 29. Positioning the solid cover 6 within the interior field of the frame is thus the same as in my other above described construction, while before the perforated tray rotates, tongue 7 acts against springs 29 extending them and swinging cover 6 away causing the ashes to drop from the rotatable elements. If the tongue is still further actuated, it strikes the end of recess 26 carrying along the perforated tray. When the tongue strikes the opposite depression 5 the cover, under the urging of springs 29, again closes upon triangular projections 9.

While I have described my specific constructions, I limit myself only as set forth in the annexed claims. Various changes may be made in specific details without departing from my invention as defined in such claims.

What I claim is:

1. In an ash receptacle, a solid cover rotatable about a longitudinal axis, and a perforated tray integral with said cover, said cover and said tray each being adapted to occupy interchangeably a predetermined position. 5

2. In an ash receptacle, a solid cover, a perforated member integral therewith, means for rotating said cover and said member about an axis, and means retaining said cover and member in a predetermined position with the cover or 10 member uppermost.

3. In an ash receptacle, an open frame, a cover fitting the opening of said frame, means rotatably mounting said cover on said frame, a perforated member integrally connected along a side 15 thereof to a side of said cover and likewise fitting the opening of said frame, a projection depending from the frame at the side thereof and cooperating with said cover when the perforated member is within the opening of said frame to 20 substantially seal the lower portion of the receptacle.

4. A removable ash tray structure comprising a frame, a solid cover mounted within said frame and rotatable therein and thereon, a perforated 25 tray having one side integral with one side of said cover, and spring means for retaining both the cover and the tray in a predetermined position.

5. In an ash receptacle, a perforated tray, a solid cover pivoted at one side to a side of said 30 tray, end members depending from said tray, spring means between said end members and cover for retaining the cover in contact with said end members and located away from said pivoted side, and means on said cover and said tray permitting a limited motion of said cover about said pivot in opposition to said spring means. 35

6. An ash receptacle comprising a main body, a frame fitting over shoulders on said body and having a central opening, friction latching means 40 on said frame and cooperating with said body, depending side members on said frame, pin supports on said side members, a rotatable assembly supported on said pin supports and comprising a solid cover and a perforated tray each of such 45 size as to completely occupy the opening of said frame, and sides, springs connecting said frame depending side members and said sides of the rotatable assembly and adapted to retain the latter in a predetermined position, and a third 50 depending projection on said frame substantially sealing the lower interior portion of the main body from a part of the upper portion when the perforated tray is uppermost while having sufficient clearance with the rotatable assembly 55 when the solid cover is uppermost to permit objects on the perforated tray to drop to said lower interior portion.

RICHARD R. KIENLE.
